GLOBE MOUNTING

Raymond R. Dupler, Toledo, Ohio

Application August 23, 1937, Serial No. 160,417

3 Claims. (Cl. 35—46)

This invention relates to globe mountings but more particularly to the mounting of a globe carried by a meridian ring or annulus, the latter being supported by a standard or the like.

5 An object of this invention is to produce a mounting for a globe-carrying meridian ring whereby the ring can be revolved relative to its support or standard to enable all portions of the globe to be readily inspected or viewed.

10 Another object of this invention is to produce a mounting for a globe-carrying ring whereby the ring can be revolved relative to its supporting standard to present different portions of the globe for inspection and also to enable the ring to be turned bodily so that the lower portion can be

15 swung upwardly or outwardly and the upper portion swung downwardly or inwardly thereby to facilitate examination of the globe.

20 A further object of this invention is to produce a mounting for a globe supporting meridian ring which can be revolved relative to its standard and can be swung about a horizontally disposed axis and can also be shifted vertically thereby to facilitate examination or inspection of different 25 portions of the globe.

Other objects and advantages of the invention will hereinafter appear and for purposes of illustration but not of limitation, an embodiment of the invention is shown on the accompanying drawing in which:

30 Figure 1 is a side elevation partly in section of a globe, its supporting meridian ring and a standard or support for the ring;

Figure 2 is a vertical sectional elevation substantially on the line 2—2 of Figure 1; and

35 Figure 3 is an enlarged transverse sectional view on the line 3—3 of Figure 1.

The illustrated embodiment of the invention comprises a standard consisting of a series of upright posts or columns 10 which are suitably secured together at a point below the upper end thereof by cross brace members 11. Resting upon an upwardly projecting dome-like portion 12 on the cross brace members 11 is a curved support

40 13 in the form of a semicircle. The support 13 is connected to opposed posts 10 by screws 14. Resting on the curved support 13 is a meridian ring or annulus 15 which has an enlarged rim or peripheral portion 16. Suitably mounted within the

45 ring 15 is a globe 17 of any suitable material which may be covered with or otherwise suitably display a terrestrial or celestial map. The globe 17 is mounted on diametrically opposed bearing members 18 to enable the same to rotate about the 50 axis so defined.

For holding the meridian ring 15 in place and enable it to slidingly revolve relative to the standard, a pair of opposed guide or bearing members 19 are connected to oppositely disposed posts 10. As shown in Figure 3, each guide member 19 has a substantially U-shaped resilient outer end portion 20 which loosely embraces the rim 17 and adjacent portion of the ring 15. Projecting inwardly from the U-shaped portion 20 is a pin 21 which is rotatable in a suitable bearing member 22. 5 This connection enables the ring 15 to be revolved freely with the lower end resting upon the curved support 13. The construction of the guide members 19 is such that the globe and meridian ring assembly can be lifted vertically as a unit to enable quick inspection or examination of the globe, because of the U-shaped guide members 20 which loosely support the ring in position and yield outwardly when the ring is lifted a sufficient distance. The pintles or pins 21 are projected through the 10 hubs of the bearings and have heads on their inner ends which abut the inner ends of the hubs, and due to the members 19 being secured to the outer ends of the pintles, all of these parts are connected as a unit. It will also be observed that 15 the annulus 15, due to its enlargement, has a resultant T-shaped configuration in cross-section.

The curvature of the support 13 is defined by the curvature of the circumference of the ring 15 so that the ring 15 can be swung about the 20 pivots defined by the guide members 19. It will be observed that the curved support 13 is disposed in a plane at substantially right angles to the plane of the ring 15. This mounting enables the lower portion of the ring 15 to be swung upwardly and the upper portion of the ring downwardly to bring the latter into engagement with the support 13. This also facilitates examination of the globe 17 by quickly bringing into unobstructed view the lower portion of the globe. 30

It is to be understood that numerous changes in details of construction, arrangement and operation may be effected without departing from the spirit of the invention especially so defined in the appended claims.

45 What I claim is:

1. A globe mounting, including a support, a globe carrying annulus, and means to connect said annulus to the support at diametrically opposite points each including a bearing, a pintle 50 carried by the bearing, a substantially U-shaped resilient member having its bight connected to the pintle, an enlarged portion on the annulus received within the U-shaped resilient member adjacent the bight portion of the latter, the arms 55

of said member receiving and engaging the annulus therebetween, whereby to provide for rotation of the annulus and instantaneous sliding thereof into and out of the resilient members, and means to restrict downward movement of the annulus.

5. A globe mounting in accordance with claim 1, wherein the annulus is of substantially T-shape 10 in cross section with the head thereof confronting the hight portion of the U-shaped member, and wherein the bearings have parts abutting the support and have further parts formed with bores that are received in sockets provided therefor in the supports, and wherein the pintles are pro-

jected through such bores and have heads on their inner ends which engage the inner ends of said parts of the bearings.

3. A globe mounting, including a support, a globe carrying annulus, combined means for mounting the annulus on the support for 5 slideable and rotatable movements with respect to said support, means to restrict downward movement of the annulus, and means to rotatably mount the globe within the annulus for movements independent of the combined mounting means, whereby the globe has three independent movements.
